UNITED STATES PATENT OFFICE

FRANK G. CARRINGTON, OF ANNISTON, ALABAMA, ASSIGNOR TO FERRIC ENGINEERING COMPANY, OF ANNISTON, ALABAMA, A CORPORATION OF DELAWARE

ANNEALING

Application filed November 7, 1928. Serial No. 317,818.

This invention relates to annealing, and more particularly has reference to a process and apparatus for annealing pipe.

The annealing of pipe as heretofore practiced has been attended by certain outstanding disadvantages. In the first place it has been directed largely to only the softening of the metal by reducing the combined carbon content of the pipe, and has disregarded all other effects of the annealing temperatures. A complete utilization of the heat treatment necessarily comprehends a regulation of the crystal size, internal stresses, oxidized coating, surface decarbonization, and blisters.

Failure to control the above factors has, perhaps, been a necessary consequence of the type of apparatus formerly employed for the annealing of pipe. The ovens used prior to this time have been of a type that render any close regulation of temperature therein impossible.

The method of inserting and maintaining the pipe in the ovens has been undesirable in several respects. The process most frequently used is to roll the pipe through the oven either by means of rollers, cams, or some other similar form of conveyor. This results in the establishment of heat transfer areas at those points where the pipe contacts with the conveying means. A further irregularity in temperature along the pipe's length is frequently produced where the oven is heated from each side, which is the conventional practice. The course of the combustion gases

in an oven of this character is such that the pipe is heated to a greater extent at the center than at either end. The result of this irregular heat distribution is that certain points along the pipe's length are fixed for the desired temperature, and all other points are subjected to a temperature either below or in excess of this temperature.

A further disadvantage in the annealing apparatus heretofore used has been an inability to regulate the temperature of the oven along its length. Burners or other heating means are spaced on the sides along the length of the oven, and necessarily at some distance from the center of the pipe, and the heating effect of these media is usually grad-

uated throughout the oven. In view of the fact that the heating means are spaced some distance from the center of the oven, there is a consequent intermingling of the gas with that from the heating medium adjacent to it. It is, therefore, impossible to accurately control the temperature along the length of the oven.

The foregoing relates to any type of pipe, and while my invention is adapted for use with a pipe cast by any of the conventional methods, it is particularly valuable for the treatment of pipes cast by the centrifugal process. With pipe that has been centrifugally cast the above disadvantages are accentuated, and in some particulars the prior methods of annealing have been found totally wanting in the treatment of this kind of pipe.

The product of a centrifugal casting operation has several marked differences from that cast by other processes. The molds employed in a centrifugal casting apparatus are usually of metal construction, or sand reinforced by a metal jacket, for it has been found that molds made entirely of sand cannot withstand the pressures generated in centrifugal casting. The presence of metal gives the mold more pronounced thermal conductivity properties, and requires that the mold be artificially cooled. These properties result in a greater tendency for the casting to be case-chilled, and consequently increase the necessity for an annealing process.

In addition, the centrifugal force generated by a rotary mold makes for a casting of considerably greater density than would be the case if the casting were made by a process other than the centrifugal method. The granular structure of the casting is closer, which, while resulting in a product of considerably greater strength, introduces into the annealing of the objects factors not ordinarily present.

To overcome the above and other disadvantages inhering in the prior art is one of the objects of my invention.

Another object is to devise a method of annealing pipe whereby the temperature of the pipe may be closely regulated at any moment

while it is in the oven, and the heating along the length of the pipe may be exactly controlled.

5 A further object of my invention is to devise a method of annealing pipe whereby the temperature of the interior of the pipe may be accurately controlled.

Yet another object of my invention is to devise an economical and efficient annealing 10 process for pipe.

A still further object of my invention is to provide an apparatus for annealing pipe in which the temperature at any point within the apparatus may be closely controlled.

15 To accomplish the above, and other important objects, as will more fully appear herein, my invention in general comprises a process and apparatus for annealing pipe that are both inexpensive and efficient, in which 20 the temperature to which both the interior and exterior of the pipe are subjected may be closely regulated along its length, and the time during which the pipe is exposed to a given temperature may be accurately regulated.

In order to insure a complete comprehension of my invention, but wishing it to be distinctly understood that various modifications may be made therein without departing 30 from the true scope of the invention, reference is made to the accompanying drawings in which the same element is referred to by similar numerals:

Figure 1 is a top view of an annealing oven 35 and associated track and power means;

Figure 2 is a side elevation view of the device shown in Figure 1;

Figure 3 is a front elevation view of the feeding end of the apparatus;

40 Figure 4 is a sectional view along the line 4-4 of Figure 1, looking in the direction of the arrows;

Figure 5 is a view along the line 5-5 of Figure 4, looking in the direction of the arrows;

Figure 6 is a view along the line 6-6 of Figure 4, looking in the direction of the arrows;

Figure 7 is a view along the line 7-7 of Figure 6, looking in the direction of the arrows;

Figure 8 is a view along the line 8 of Figure 4, looking in the direction of the arrows;

Figure 9 is a detailed view of an opening 55 in the oven;

Figure 10 is a sectional view of a modified support for pipe;

Figure 11 is a view in detail of a reciprocating plate.

60 Referring in more particularity to the drawings, and especially to Figures 1 and 2, there is shown an oven 1, made of fire brick or other refractory material adapted to withstand, and conserve, the heat introduced into the interior of the oven. The walls and general

construction of this oven are such as to prevent an escape of the heat. A layer of insulating brick (not shown) is preferably provided around the exterior of the oven. As is shown in Figure 1, the oven is of rather restricted 70 width, permitting an economy of space in this respect. The height of this oven, as shown in Figure 2, is such as to receive a pipe when suspended vertically.

Ports 2 are provided at close intervals along 75 the length of the oven, and are positioned near the base of the oven as shown more particularly in Figure 2. By providing these ports at close and regular intervals, it is possible to control the temperature along the 80 length of the oven by regulating the heating means at each port. If, for instance, it were desired to heat the oven uniformly along its length, a uniform temperature at each of the ports would insure this, for the proximity of 85 the ports prevents any areas of lag between them.

Mounted in each port 2 is a burner 125. Referring more particularly to Figure 6, it will be noted that these burners are similar 90 to the conventional Bunsen burners, comprising a jet 126 which supports, by means of a spider or other suitable means, a casing 127. Adjacent the casing 127, a plate or disc 128 is mounted upon the jet 126, which serves 95 to maintain a strong draft of air through the casing 127, and thus increase the combustion of the gas dispersed from the jet. The jet is fed with the gas by a supply line 129. Each burner is provided with a regulating 100 means (not shown) whereby the amount of gas supplied each burner may be controlled and consequently the flame issuing therefrom. In operation, a draft of air is set up in the oven, and fresh air entering through the ports 105 2 is heated by the flames from the burners 125. This air rises and passes out of the furnace as will be later described.

It is, of course, within the purview of my invention, to substitute other heating means 110 for the burners here shown. For instance, the temperatures may be obtained by supplying the ports with heated air or an inert gas.

In Figures 1 and 2 I have shown diagrammatically doors 3 and 4 at the receiving and discharging ends of the oven respectively. These doors are adapted to retain the heat within the oven, and may be of a hinged or roller type, operated either mechanically or 115 manually. In the usual operation, the door 3 is normally maintained closed, and is opened only when a pipe is inserted in the oven. The same applies with respect to door 4 when the pipe is discharged from the oven.

Spaced along both sides of the length of the oven are chimneys 5 for the emission of the heated air or gases after they have performed their function, and the heat emerging from 120 these chimneys may be either dispersed into 125 130

the atmosphere, or recycled and reheated to effect an economy. The exact positions and number of these chimneys are optional, depending upon various factors. They should, however, afford an adequate outlet for the heated air after passing over the pipe, and, if opening into the atmosphere, should be of such construction as to produce sufficient draft to the desired circulation within the oven. If the air is recycled, an appropriate pump or fan is installed in the system to insure the necessary draft, and it may be preferable to provide such mechanical means to force the air into the oven even if the chimneys open into the atmosphere.

As shown in Figures 4 and 6, the oven comprises side walls 6 and a ceiling 7. The ceiling 7 is provided with a slot 8 centrally positioned and running longitudinally of the oven. This slot 8 is of a restricted width, and its function will be described hereinafter.

Serving as a support for both the oven and also for a conveying mechanism are a series 25 of buckstays 9 oppositely disposed on each side of the oven along its length. These buckstays comprise pairs of channel-bars, suitably imbedded in the foundation. These buckstays are particularly desirable in view of the 30 fact that the slot 8 runs the entire length of the oven forming in effect overhanging projections on the side walls 6. Spanning each oppositely disposed buckstay 9, and at a suitable distance above the ceiling 7 is channel-bar 11, which, of course, is properly secured to the supports 9.

The cross sectional view of the oven, set forth in Figure 6, shows the ports 2 through which air is introduced into the interior of 35 the oven. These ports are connected to vertical channels 12, which extend to substantially the ceiling 7. As indicated by the dotted lines in Figure 4, the channels 12 are preferably of the same width as the ports 2.

Opening from each channel 12 into chamber 13 of the oven are ports 14. These ports, as will be observed from Figure 6, are spaced at predetermined intervals along the height of the channels 12. The intervals between 45 the ports 14 are preferably uniform, so that when all of the ports are open, there will be an introduction of heat into the chamber 13 that is substantially the same along the height of the chamber. It is to be noted that 50 these ports 14 are oppositely disposed, and, as the burners 125 in the opposite ports 2 will be equally regulated, the pipe traversing the oven will be subjected to a substantially uniform heat on opposite sides.

As the air passes through the ports 2, it enters the channels 12. From the channel 12 it will pass out through the various ports 14 into the chamber 13 according to the degree to which the ports 14 are opened.

The amount of gas entering the chamber

13 from any given port 14 may be controlled by means of blocks 15 positioned in the ports 14, and which are shown in more detail in Figure 8. These blocks 15 are substantially the height of the ports 14, and, while shown 70 as not being anchored in the ports 14, may, nevertheless, be provided with a pivot about which they may swing. The position of these blocks 15 within the ports 14 may be varied as shown in Figure 8, and, depending 75 upon the position of the blocks, the amount of gas introduced into the chamber 13 may be varied.

Running from the outside of the walls 6 to the channels 12 are openings 16. One of 80 these openings is located opposite each of the ports 14. A rod or other suitable implement may be put through these openings 16 to move the blocks 15 into the desired positions. Thus an operator may regulate the blocks 15 85 accurately and as frequently as necessary. Manipulation of the blocks is possible, therefore, with a minimum exposure of the operator to the heat of the oven.

This arrangement also prevents an escape 90 of heat from the interior of the furnace, for there is provided, as shown in Figure 9, in detail, a cover for each of the openings 16. This cover comprises a body portion 17 of sufficient size to totally cover the opening 16, 95 and is pivoted as at 18 to permit of a ready opening and closing of the passage. A lip 19 is provided, which fits within a bracket 21 mounted on the side of the wall, which normally maintains the cover in a closed position, 100 completely preventing a passage of heat through the opening 16.

It will be readily seen that by means of the arrangement of the ports 14 and the blocks 15, there may be a close regulation of the heat at any point within the furnace. The proximity of the ports 14, not only to those above and below, but to those on either side, obviates any possibility of lags between different ports. The blocks 15 permit a nicety 105 of control of the heat emitted from any given port. While ordinarily it is desirable that a uniform temperature exist along the entire length of the pipe, under certain circumstances it may be desirable to vary the heat 110 along the length of the pipe, for instance the bell of the pipe, by reason of its greater thickness, may require a more intense heat treatment than is necessary for the barrel. This can be readily taken care of by opening 115 the top ports 14 more than the lower ones.

In operation it is usually necessary to have the lower ports opened to a greater extent than the upper ports, and the openings are usually graduated accordingly. This is necessitated by the tendency of the heated gas upon emerging from the port 2 to pass upwardly through the channel 12, rather than to pass evenly into the chamber 13 through the various ports. However, the various po- 120

sitions of the blocks 15 will depend upon operating conditions, and can be readily adjusted accordingly.

Immediately adjacent the ceiling 7 and in 5 the same vertical planes with the ports 14 are channels 22, which extend toward the outside wall 6 and empty into a channel 23, which runs substantially the length of the oven and, of course, is closed at both ends. A 10 vertical channel 24 extends from the channel 23 to the flue 25 of each of the chimneys 5. As above stated, the number and positions of the chimneys 5 are optional, depending upon various conditions, and consequently the same 15 considerations apply to the channels 24.

The channels 22, 23 and 24 conduct the heated air from the chamber 13 to the chimneys 5, from which latter the air is either dispersed into the atmosphere or recycled. By 20 providing a channel 22 directly above each row of ports 14 the air from any given row of ports 14 rises within the chamber 13 and passes out of the oven through that chamber 22 which is above the inlet ports. This arrangement prevents any extended overlapping and intermingling of air from the different ports, and permits a close control of the temperature within any given area.

Referring particularly to Figures 2 and 6, 30 the operation of the oven is readily discernible. For purposes of economy it is usually desirable to heat the pipe as rapidly as possible to the maximum temperature and then control the cooling. The rapid heating saves 35 time, which is essential in this operation, when the number of pipes to be treated is considered. Consequently, the burners 125 in those inlet ports 2 at the entrance end of the oven will be regulated to produce the greatest 40 heat, and the flames of the burners in the other ports will be regulated according to the exigencies of operation. There will, therefore, be a close control of the temperature along the entire length of the oven.

The next consideration then is a control of 45 the air that enters the chamber 13 from the ports 14. The arrangement shown in Figure 6 provides adequate means for this regulation. If it is desired to heat the pipe at the same rate along its length, the blocks 15 will 50 be adjusted in the ports 14 substantially uniformly, making proper allowance, however, for the tendency of the heated air to rise to the top of the chamber 12 rather than pass 55 uniformly through the various ports 14. This regulation of the blocks 15 is effected by inserting a rod through the openings 16 and moving the blocks to their proper positions.

The gas discharged from any row of ports 60 14 is confined to that area of the oven, for in the absence of unexpected drafts within the oven it rises and passes out of the oven through the channel 22 above the ports.

As above stated, the slot 8 in the ceiling of 65 the oven is of a restricted size, and very little

of the hot gas escapes therethrough. As has also been heretofore described, the doors 3 and 4 are closed except for a moment when a pipe is inserted or withdrawn from the oven.

As indicated in Figure 6, it will be noted that 70 these doors are of a relatively small size, sufficient, however, for the free passage of pipe therethrough, a large portion of the chamber 13 being closed by an end wall 26.

The pipe is passed through the oven and the 75 various zones of temperature therein established by the heating means as above described. The conveying mechanism for the pipe comprises a collar 27 of heat resistant metal, and is of slightly larger diameter than 80 the barrel of the pipe. This collar may be readily slipped over the spigot end of the pipe and passed along the barrel until it engages the bell.

The pipe may therefore be suspended by 85 its bell during its passage through the oven. By engaging only the bell, there is only one area of heat conduction set up along the entire length of the pipe. Furthermore, this area is on the bell, which portion of the pipe 90 is best able to withstand such a condition. The increased thickness of the bell is sufficient to insure requisite strength, even in the presence of inadequate annealing. As above 95 stated, the prior processes have set up heat conduction areas along the barrel of the pipe, which are detrimental, and are avoided herein.

As shown in Figures 4 and 6, the collar 27 is provided with studs 28 oppositely disposed 100 on its outer circumference. A stirrup 29, made of a heat resistant metal and having hooks 31 adapted to engage the studs 28, supports the collar 27 and the pipe 32 contained therein. The stirrup 29 is engaged by a hook 105 33 which extends upwardly through the slot 8 and is supported in a carriage designated generally 34. As above stated, the slot 8 is relatively narrow and of a size sufficient only to receive the hook 33, with an allowance for 110 slight displacement of the hook.

When casting plain-end pipe, a modified form of support such as shown in Figure 10 may be used. A straight shaft 131 is substituted for the hook 33, which extends 115 through the pipe 32. A frusto-conical member 132, slidable on the shaft 131, supports the pipe, while a similar inverted member 133 engages the top of the pipe to maintain it in position. The members 132 and 133 are made up of hubs 134, which are slidable on the shaft 131, but which are provided with suitable means (not shown) for fixing them with respect to the shaft. Spokes 135 and 136 extend from the hubs 134 120 and support the converging walls 137.

As above stated, the prior annealing processes have been undesirable in that the pipe 125 has been supported by the barrel. This contact on the exterior of the barrel sets up heat 130

transfer areas which render the casting inferior. The modified form of support shown in Figure 10, suspends the pipe with its exterior free from any contact whatsoever. The 5 points of engagement between the support and the pipe are very limited and occur only at the ends of the interior of the pipe. By providing spokes 135 and 136, rather than solid plates, a free circulation of air through 10 the pipe is permitted. It is, of course, obvious that the modified form of support may be used with bell and spigot pipe as well as with plain-end pipe.

Referring particularly to Figure 7, the carriage 34 is of cast iron or other suitable material and comprises a frame member 35 having a comparatively low front and a high rear, the purposes of which will be later discussed. Secured in the frame 35 is a pair of 20 stationary axles 36 on which are rotatably mounted grooved rollers 37 adapted to fit and roll upon a track made up of a pair of spaced tubes 38.

The frame 35 is provided with a circular recess 39 intermediate the two axles 36. A bearing 41 fits within the recess, and is provided with a ball race adapted to receive a set of brass or nickel steel ball bearings 42. Another bearing 43, likewise provided with a 30 ball race to correspond to the one in bearing 41, is also fitted within the recess 39.

Securely fitting over the bearing 43, and adapted to rotate in the recess 39, is a socket 44. The socket 44 and bearings 41 and 43 35 are preferably composed of machined steel. The body of the socket 44 is recessed as at 45 to receive a machined steel ball nut 46 on the end of the hook 33. The ball nut 46 and the recess 45 form a ball and socket joint for the 49 hook 33. The frame 35, bearings 41 and 43 and the socket 44 are cut away in order to form a frusto-conical opening through which the hook 33 extends. This permits of a limited movement of the hook 33 with respect 45 to the carriage occasioned by jarring or swinging of the pipe.

The socket 44 is secured in its seat by means of a top plate 47 which has a downwardly projecting annular flange 48 fitting within a 50 flange 49 on the socket 44. This prevents any displacement of the socket 44 and insures a tight seating of the socket within the recess 39. The top plate 47 is secured to the body portion 35 by means of bolts 51 or other 55 suitable fastening means.

As above stated, the front portion of the carriage 34 is lower than the rear, and the top plate 47 extends for a certain distance to the rear of the front on an inclined plane 60 as at 53, and thence on a plane parallel to the horizontal plane of the carriage to the elevated rear end of the carriage as at 54. It will be observed that the top of the portion 54 is flush with the top of the rear end of the 65 carriage. The back of the carriage near the

top is cut away as at 55 forming a socket 56 which will be hereinafter described.

The socket 44 is provided with star-shaped fingers 57 as best shown in Figure 5. These fingers engage arms which will be later described, and cause a rotation of the socket 44. The provision of ball bearings in this socket arrangement decreases the friction attendant upon such rotation and permits of a ready revolution of the socket. Notwithstanding 70 the fact that the hook 33 is supported in the socket 44 by means of a ball and socket joint, the rotation of the socket 44, particularly when the hook 33 is supporting a pipe, will 75 effect rotation of the pipe.

As has been heretofore pointed out, the heat is introduced into the chamber 13 from the opposite side walls, and this provision for rotating the pipe during its passage through the oven insures that the pipe is subjected to 80 a uniform heat treatment circumferentially. In Figure 5 the sockets 44 are shown provided with five fingers 57, which means that the pipe is rotated by fifths. The number of fingers may be varied, of course, although I 85 have found that five is the preferable number.

While I have shown a highly satisfactory form of carriage, it is, of course, obvious that other means for supporting the pipe while traversing the oven may be employed.

Bent around the axles of each carriage are rods or bands 58. These rods or bands depend from the axles and support a plate 59 composed of fire clay or other suitable refractory material. Hooks 61 are embedded 100 in the block 59 and are appropriately linked to the rods 58. An aperture 62 is provided in the block 59 through which extends the hook 33, or shaft 131. This aperture is of restricted size and permits only limited movement of the hook 33 with respect to the plate 59.

As is shown in Figure 6, the plate 59 is supported a short distance above the top of the ceiling 7, and is for the purpose of diverting any hot gas that might pass from the furnace through slot 8. As has been stated, very little heat from the chamber 13 escapes through the slot 8, but the plate 59 protects the carriage 34 and associated mechanism 110 from what heat does pass through the slot 8.

The tube rails 38 are supported by standards 63, and are secured to these standards by welding, brazing or other appropriate fastening means. The standards 63 are provided with flanges 64 in which pockets 65 are formed for the reception of the rails. These standards are secured to the cross-bars 11 by means of bolts 66, although it is, of course, to be understood that rivets or other equivalent fastening means may be employed.

A pair of spaced bearings 67 is provided on each cross-bar 11, in which bearings are journaled rollers 68 provided with flanges 69. The rollers 68 support an I-beam 71, which 130

runs the length of the annealing oven. The I-beam 71 rests upon the rollers 68 with its top slightly spaced from the cross-bar 11 in order to prevent any friction when the

5 I-beam reciprocates, as will be hereinafter pointed out. The flanges 69 on the rollers 68 serve as guides for the I-beam and confine any movement of the I-beam to a reciprocation or longitudinal movement.

10 As shown more particularly in Figure 7, spaced at intervals along the I-beam 71 are brackets 72 which are secured thereto by bolts, rivets, brazing, welding or other appropriate securing means. One end of the bracket 72 is enlarged as at 73, providing a socket for a pivot pin 74. The pivot pin 74 passes through the end of an arm 75 and permits an oscillation of the arm 75 about the pin 74 as a pivot. As shown in Figure 7, the arm 75 is 15 adapted to fit into the socket 56 on each carriage.

A movement of the I-beam to the right, as shown in Figure 7, therefore pushes the carriage 34 in the same direction. When the 20 I-beam 71 is moved to the left, the arm 75 slides along the top of the succeeding carriage 34 and fits into its socket 56. This carriage then may be moved to the position occupied by the immediately preceding carriage. It will, therefore, be seen that reciprocation of the I-beam 71 results in a passage of the carriages from left to right the 25 length of the oven. When no carriages 34 are in the oven, the arm 75 swings vertically 30 from the bracket 72, but the first carriage to enter the oven readily raises the arm 75 in position for operation. The top plate 47 of the carriage 34 is inclined as at 53 in order to permit a proper engagement of the arm 35 75 in the socket 56 of the preceding carriage.

Reciprocation of the I-beam 71 is effected by the mechanism shown in Figures 1 and 2. This comprises a rod 76 pivoted to a bracket 77 mounted on the I-beam 71. The opposite 40 end of the shaft 76 is pivoted to a bracket 78 integral with or secured to an eccentric strap 79. The strap 79 fits upon an eccentric 45 81 which is mounted upon a shaft 82. The shaft 82 is supported in standards 83 mounted upon a suitable base 84. Rotation of the shaft 82 therefore imparts a reciprocatory motion to the I-beam. The base 84 must be of such a height as to place the eccentric in an operative position for the I-beam 71. A 50 gear 85 is keyed on the shaft 82, and meshes with a gear 86 on a motor 87 or other suitable driving means.

The I-beam 71 is therefore reciprocated when the motor 87 is running. This reciprocation of the I-beam causes the arm 75 to engage one of the carriages 34 and move it the 55 length of the stroke of the I-beam 71. On the return stroke the arm 75 passes over the succeeding carriage and engages its socket. 60 The succeeding carriage is then moved to the

position formerly occupied by the preceding carriage, which in turn has been moved one stroke further on.

Referring again to Figure 6, there is shown a pipe 88, which passes through the side wall 6 of the oven. This pipe is provided with an elbow 89 in which is threaded a short section of pipe 90. This section 90 projects upwardly and immediately in the path of the pipe 32 as it is passed through the oven. A 70 minimum clearance is allowed between the spigot end of the pipe and the top of the section 90, although provision should be made for any possible irregularity in the position of the pipe.

The pipe 88 is joined to a feeder 91, which runs the length of the oven and conveys a heated air or gas to the various pipes 88 positioned along the oven. The particular pipe 88 shown in Figure 6 is threaded in a four-way joint 92. A section 92' is threaded in the joint 92 opposite the pipe 88, and its other end connects with a valve 93 for regulating the admission of the heating medium into the feeder 91. Tapped into the joint, and perpendicular to the pipes 88 and 92' is the feeder 91. The valve 93 receives the heating medium from a pipe 94, which is connected to a suitable source of hot gas or air. This may be an independent supply, or may be drawn 95 off from the chimneys 5 and reheated.

The valve 93 is provided with a control stem 93' which, when rotated in one direction, opens the valve and when rotated to a position in the opposite direction, closes the valve. 100 Connected to the stem 93' by a suitable coupling 95 is a shaft 96 journaled in bearings 97, which are mounted upon a buckstay 9. Thrust bearings 98 are also provided in addition to the bearings 97, in order to prevent 105 any axial movement of the shaft 96. This shaft may be bent as shown in Figure 6 to form a lever 99, or an independent lever 99 may be provided and suitably secured to the shaft 96.

Mounted on the free end of the lever 99 is a sleeve 101, which telescopes over a rod 102. The rod 102 is bent as at 103, and the bent portion fits within a slot in a plate 104, mounted on the I-beam 71.

Referring to Figure 11, the slot 105 in the plate 104 is of a length to permit reciprocation of the plate for substantially the length of the stroke of the I-beam 71 without contacting with the rod 102. However, at the completion of the stroke, the respective ends of the slot engage the rod 102 and impart to it a slight movement. This movement is transferred through the telescope arrangement to the lever 99, which in turn rotates the shaft 96 and stem 93' of the valve. The valve is then either opened or closed. The sleeve 101 permits the rod 102 to telescope within it, and thus compensates for the change in length 125 130 135

necessitated by the slight movement of the lever 99.

In actual operation it is desirable to discharge heated gas from the section 90 during 5 all of the time when the pipe 32 is stationary. Referring to Figure 7, this is at the completion of the stroke of the I-beam 71 to the right. Just prior to the end of the stroke to the right, the plate 104, acting through the 10 various levers and shafts, opens the valve. This valve remains open until practically the completion of the return stroke to the left, for the slot 105 and the plate 104 provide a means for free movement of the I-beam 71 15 during the major part of its stroke, without a corresponding movement of the rod 102. Just prior to the completion of the stroke to the left the plate 104 contacts with the rod 102 and forces the rod along with it. This 20 in turn closes the valve, and the valve remains closed during substantially all that time when the carriages 34 are in motion.

It will, therefore, be seen that this arrangement provides for an emission of the hot 25 gas or air from the section 90 during that period when a pipe 32 is above it. The section 90 disperses the gas inside of the pipe (there being little opportunity for an escape of the gas around the outside) and provides 30 a means of closely regulating the heat condition of the interior of the pipe as well as the exterior. Of course, without this arrangement the interior would be subjected to the more or less same degree of heat treatment 35 as the exterior, but various factors enter which frequently result in a different treatment inside of the pipe from that obtained on the outside. This, of course, is particularly true in the case of an annealing 40 process similar to my invention, for the hot gas is directed upon the pipe from either side, and consequently the inside of the pipe gets only an incidental heat treatment. The provision which I have made enables an operator to regulate the interior temperature of the pipe to conform exactly to that on the outside, or at any desired ratio.

It is, of course, to be noted that other 50 means may be employed to synchronize the discharge of the gas from pipe 90 with the positioning of the pipe 32. This might comprise a chain of gears connected with the eccentric 81, or other appropriate means.

Referring particularly to Figures 1 and 2, 55 it will be observed that the track 38 is continuous. After it passes the discharge end of the oven it curves as at 106 and then proceeds in a straight direction as at 107 for a short distance. From approximately the 60 discharge end of the oven the track slopes downwardly and the carriages by gravity proceed of their own accord. This grade continues around another curve 108 and thence down the straightaway 109. Appropriate standards 111 from which depend

brackets 112 similar to brackets 63 are provided to support the track.

At some place along this track provision may be made for removing the pipe from the carriage, preferably by disengaging the stirrup 29 from the hook 33. This may be done manually or by mechanical means. At the end of the straightaway 109 the track curves as at 113 and thence proceeds in a horizontal plane for a short distance as at 114. 70

An upwardly inclined section 115 serves to raise the carriages 34 to slightly above the level of the track 38. A more or less graduated downward slope 116 provides a means for the carriages 34 to roll down to the receiving end of the oven. As above pointed out, the carriages are moved along the length of the oven by means of the I-beam 71 and rods 75. 80

The carriages 34 are forced up the incline 85 115 by means of a belt 117. This belt is frictionally mounted upon rotatable members 118, 119 and 120, one at least of which is actuated by appropriate means not shown. A supporting bracket 121, held by means of 90 standards 122 serves to rotatably support the members 118, 119 and 120. The belt 117 is provided with blocks 123 which engage the rear ends of the carriages 34 and push them up the incline 115. 95

It will therefore be seen that this annealing process is a continuous operation, and, as far as the passage of the pipe through the oven is concerned, requires supervision only to the extent of loading the pipe upon the carriages 34 and removing them therefrom. These two operations might well be carried on at approximately the same location, preferably along the stretch of track 114. 100

Referring to Figure 4 in particular, it will be observed that a series of fingers 124 are spaced along the I-beam 71, preferably adjacent the several plates 72, and extending downwardly a sufficient distance to engage the rotatable fingers 57 of the socket 44. On 105 each return stroke the arm 124 engages a finger on the succeeding carriage, which results in a partial rotation of the pipe prior to each step through the oven. This insures a uniform circumferential heat treatment of the 110 pipe. 115

From the foregoing, the operation of my invention is apparent. At the beginning of the annealing process the motor 87 and the driving means for the belt 117 are started. 120 Collars 27 are slipped over pipes until they engage the bells thereof, and the stirrups 29 are fastened around the studs 28. The pipe may then be placed upon the carriages 34 by placing the stirrups on the hooks 33. As 125 above stated, this operation is preferably carried out along that section of the track 114. As the carriages are loaded they may be moved until they are engaged by one of the blocks 123 and hoisted to the track 116.

From thence they coast down to the track 38.

In the meanwhile the blocks 15 have been adjusted in the various ports 14 to permit the desired discharge of air from any given port, and thus regulate the heating effect along the length of the pipe. Preferably, opposite ports 14 will be correspondingly controlled.

With the ports 14 properly opened, the burners 125 may be regulated. The air entering the ports 2 will be heated and will pass through the channel 12 and ports 14 into the chamber 13 of the oven. Each burner 125 may be regulated quite independently of those in the other ports 2, and thus effect the gradient in temperature along the length of the oven. As the first carriage 34 is ready for the oven the door 3 is opened only long enough to permit its entrance, and immediately closed until the following carriage is ready for entrance. As soon as the carriage enters the oven, it is picked up by the leftmost arm 75 and carried along with the forward stroke of the I-beam 71. On the return stroke the next arm 75 picks it up and moves it one stroke further, and so it progresses through the oven.

When the first carriage enters the oven, the heating medium is introduced into the pipe 94, and as each pipe is standing still and waiting for the next arm 75 to engage it, its interior is subjected to a heat treatment by the gases emitted from the section of pipe 90. Also, at the time that the pipe 32 is stationary, on the return stroke of the I-beam 71, it is subjected to the full force of the heat emerging from the ports 14, for it is then directly opposite the row of ports.

As has been heretofore pointed out, the design of my invention is such that the temperature within a given zone of the chamber 13 may be very closely regulated. The provisions made for regulating the temperature of the incoming gas, and the further provision for the control of that gas when it has once been introduced into the chamber 13, and until its passage therefrom through the channel 22, make this close regulation possible.

By reason of the nicety of control of the heat within the chamber 13 it is possible to control the various properties of the casting which are affected by heat treatment. There is also the time factor in any annealing process, and this, of course, can be suitably regulated by controlling the speed of the motor 85.

While the pipe is traveling through the oven, it is rotated about its longitudinal axis, and consequently each portion of its circumference is subjected to the same heat treatment. There are no areas of conduction along the length of the pipe, except that portion of the bell contacting with the collar 27.

The pipe is, therefore, subjected to a uni-

form temperature both along substantially its entire length, and also about its circumference. This obviates any flaws in the pipe resulting from a non-uniform heat treatment.

When a pipe is about to emerge from the oven the door 4 is opened and immediately reclosed after the exit, thus retaining the heat within the chamber 13 and also preventing drafts within the chamber. The carriage then rolls down the inclined track and the pipe is removed.

The advantages of my invention are apparent. The economical and efficient apparatus and process, as herein set forth, requires a minimum of labor for the operation thereof. It is to be noted that I have provided an apparatus in which there is a minimum of wear and need for replacement, as well as being economical in initial construction. The arrangement herein insures in the first place, a uniform heat treatment of the barrel of the pipe both along its length and in circumference, and secondly, provides an apparatus in which the temperature of pipe at any given minute during its passage through the oven may be exactly controlled. As has been stated, this means that the character of the finished product may be accurately predicted.

Although I have shown in the accompanying drawings and described in the specifications the preferred embodiment of my invention, it is, of course, apparent that the broad conception of my invention is not confined to the details hereinbefore described, and that various modifications may be made therein without departing from the true scope and spirit of the invention.

I claim:

1. An annealing apparatus comprising a tunnel-like chamber, means for moving articles to be annealed through said chamber, a plurality of vertical flues positioned in the walls of said chamber, a plurality of vertically spaced ducts placing each of said flues in communication with said chamber at a plurality of points, a source of heat for each of said flues and means for selectively regulating the amount of heat passing from each of said flues through the several ducts.

2. In an annealing process for bell-ended pipe comprising passing a pipe in a horizontal path while vertically suspended from its bell end with its bore open at both ends and progressively subjecting the pipe to zones of different temperatures.

3. In an annealing process for bell-ended pipe comprising passing the pipe while suspended vertically from its bell end with its bore open at both ends through successive zones of different temperatures, and rotating the pipe about its axis while passing through the zones.

4. In an annealing process for pipe comprising passing a vertically suspended pipe in

a horizontal path, progressively subjecting the exterior of the pipe to zones of different temperatures and progressively subjecting the interior of the pipe to other zones of different temperatures.

5 5. An annealing apparatus for pipe comprising an oven, heating means spaced longitudinally of the oven for providing zones of different temperature within the oven, means associated with the heating means for controlling the temperature vertically of the oven, and means for passing a vertically suspended pipe progressively through the oven.

10 6. An annealing apparatus for pipe comprising an oven, heating means spaced longitudinally of the oven for providing zones of different temperature within the oven, means associated with the heating means for controlling the temperature vertically of the oven, a support for suspending a pipe vertically within the oven, and means for progressively moving the support through the oven to expose the pipe to the different temperature zones.

15 7. An annealing apparatus for pipe comprising an oven, heating means spaced longitudinally of the oven for providing zones of different temperature within the oven, means associated with the heating means for controlling the temperature vertically of the oven, a support for suspending a pipe vertically within the oven, means for progressively moving the support through the oven to expose the pipe to different temperature zones, and means for rotating the support.

20 8. An annealing apparatus for pipe comprising an elongated oven, means for heating the oven, means for passing a vertically suspended pipe through the oven, and means located below the path of travel of the pipe for heating the interior of the pipe.

25 9. An annealing apparatus for pipe comprising an oven, heating means spaced longitudinally of the oven, a vertical support within the oven so constructed and arranged to engage an enlargement upon the circumference of the pipe without materially obstructing the bore of the pipe, and means for moving the support through the oven.

30 10. An annealing apparatus for bell-ended pipe comprising an oven, heating means spaced longitudinally of the oven, a carriage mounted above the oven, means carried by the carriage and extending into the oven and engaging the bell end only of the pipe without materially obstructing the bore of the pipe, and means for moving the carriage.

35 11. An annealing apparatus for pipe comprising an elongated oven, a series of vertical burners mounted within and spaced adjacent the bottom of said oven, a support for suspending a pipe vertically within the oven, and means for imparting a step-by-step movement to said support to sequentially dispose the pipe over successive burners.

12. An annealing apparatus for pipe comprising an oven, a support within the oven for sustaining a pipe in a vertical position but affording a continuous passage for heated gas throughout the interior of the pipe, and means for moving the support through the oven.

70 13. An annealing apparatus for pipe comprising an oven, a support within the oven for sustaining a pipe in a vertical position but affording a continuous passage for heated gas throughout the interior of the pipe, means for moving the support through the oven, and heating means within the oven located below the lower end of the pipe.

75 80 In testimony whereof I affix my signature.
FRANK G. CARRINGTON.
